(57) **CLAIM**

The ornamental design for cable organizer, as shown and described.

DESCRIPTION

FIG. 1 is a perspective view of a cable organizer showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; the right side being a mirror image; and,

FIG. 7 illustrates the cable organizer used in a plug.

The broken lines in the drawings are for illustrative purposes only and form no part of the claimed design.
